Primary Examiner — Rosemary K Tarcza*Assistant Examiner* — Nathaniel D Buckner(74) *Attorney, Agent, or Firm* — Zollinger & Burleson Ltd.(57) **CLAIM**

The ornamental design for a mounting bracket for tunnel light, as shown and described.

DESCRIPTION

FIG. 1 is a perspective view of a first embodiment of the mounting bracket for tunnel light showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines shown in the figures illustrate portions of the article that form no part of the claimed design.
